UNITED STATES PATENT OFFICE.

ALBERTINE RUELLAND, OF NEW YORK, N. Y.

DESIGN FOR AN ELECTRIC IRON.

59,286.

Specification for Design.

Patented Oct. 4, 1921.

Application filed May 7, 1921. Serial No. 467,584. Term of patent 14 years.

To all whom it may concern:

Be it known that I, ALBERTINE RUELLAND, a citizen of France, residing at New York, borough of Manhattan, in the county and State of New York, have invented a new and original Design for Electric Irons, of which the following is a specification, reference being had to the accompanying drawings, forming part thereof.

Figure 1 is a plan view of an electric iron, showing my new design; and

Figs. 2 and 3 are side elevations of the same.

What I claim is:

The ornamental design for an electric iron as shown.

ALBERTINE RUELLAND.
